UNITED STATES PATENT OFFICE.

CHARLES EDWARD CHESTNUT AND WILLIAM ALBERT HENDERSON, OF CALGARY,
ALBERTA, CANADA.

TUBE-CLEANER.

1,379,852.

Specification of Letters Patent. Patented May 31, 1921.

Application filed September 27, 1920. Serial No. 413,224.

To all whom it may concern:

Be it known that we, CHARLES EDWARD CHESTNUT and WILLIAM ALBERT HENDERSON, subjects of the King of Great Britain, 5 and residents of Calgary, in the Province of Alberta, in the Dominion of Canada, have invented certain new and useful Improvements in a Tube-Cleaner, of which the following is a specification.

10 Our invention relates to improvements in a tube cleaner, the objects of which will be apparent to those versed in the art by the following description, reference being made to the drawing forming part of this application.

The view shown in the accompanying drawing illustrates clearly the construction of the device and shows the relative parts in perspective.

20 Referring more particularly to the drawings, the two spring members *a* terminate in disks *b*, adapted to cut the incrustation and remove it from the tube, said disks traveling forward with a rotary motion and 25 having a screw action while the spring members *a* maintain a constant pressure toward the tube surface. Cutters of this kind have been in use for a considerable time and have been found difficult to operate.

30 To facilitate the operation and improve the efficiency of the device spring members *a*, having their edges adapted to engage

the surface of the tubes in a plane perpendicular to that of the cutting disks *b*, are provided; said members projecting beyond 35 the cutting disks *b*, are turned inwardly so as to facilitate insertion of the device within the tubes. These two sets of spring members *a*, are mounted in a base *d*, which is in turn mounted in a rotary device which 40 does not form a part of this invention and is not therefore illustrated.

From the foregoing description it will be apparent that the device has as its object the cutting away of the incrustation and the 45 cleaning of the tube at one and the same time.

Having described our invention, what we claim is—

A tube cleaner, consisting of a pair of 50 spring members with cutter portions at their outer ends, said cutter portions having overlapping parts forming substantially sections of a worm; additional spring members bearing against said cutter portions at the 55 outer edges thereof, and a handle or holder to which the inner ends of all the spring members are secured, said additional spring members having scraper edges.

CHARLES EDWARD CHESTNUT.
WILLIAM ALBERT HENDERSON.
